MECHANICAL BINDING

Clarence D. Trussell, Turnwood, N. Y.

Application March 17, 1950, Serial No. 150,220

3 Claims. (Cl. 129—1)

1

The invention herein disclosed relates to mechanical bindings of the type shown and described in co-pending patent applications, Serial No. 602,985, filed July 3, 1945, Patent No. 2,502,493, dated April 4, 1950, and Serial No. 108,903, filed August 6, 1949, in which the binder rings are provided by a series of flexible fingers projecting from one side of a tubular backbone or rib and having their free ends engaged in slots formed in the opposite side of the rib.

In those particular bindings the flexible spring fingers are usually given a "set" which will cause them to stand in the open relation ready to receive the leaves or the filler which is to be bound.

In such constructions, with the rings biased in the opening direction, some means are required to secure the ends of the fingers in the ring closed position, such as the interlocking retainer shoulders on the fingers and tubular rib, as disclosed in those patent applications.

The subject of the present patent application is a mechanical binding of the type considered in which the fingers hold closed in their ring forming relation of themselves and without the need for special locking or interlocking elements.

Special objects of the invention are to provide such a construction in a simple, inexpensive form that can be made up at low cost with simple, inexpensive equipment and which will be truly practical and efficient in every way.

A further special object of the invention is to provide a structure which can be used either as a permanent binder or be opened up and used, if desired, as a loose leaf binder.

Other desirable objects attained by the invention are set forth or will appear in the course of the following specification.

The drawing accompanying and forming part of the specification illustrates a present commercial embodiment of the invention. Structure, however, may be modified and changed in certain respects, within the intent and scope of the invention as hereinafter defined and claimed.

Figure 1 in the drawing is an end view of one of the bindings, with the tubular rib portion shown broken away and in section.

Figure 2 is a broken plan view of the binding with one of the ring forming fingers shown in section.

Figure 3 is a broken side elevation of the binding.

Figures 4 and 5 are broken sectional views illustrating die mechanism for opening the normally closed rings and showing such mechanism as first positioned and then as actuated to si-

55

Means for such purpose are shown in Figures 4

multaneously open all the ring forming fingers.

Figure 6 is an end view partly in section illustrating the binding closed with the filler in position.

5. The binding shown is made up of a tubular rib 7, having integrally attached ring forming fingers 8 projecting from one side of the same and adapted, in the ring forming relation, to project into fully seated engagement in slots 9 in the opposite side of the same.

This binding may be produced in plastic or other materials and may be manufactured according to methods disclosed in co-pending patent application, Serial No. 150,219, filed March 15, 1950.

In all events, the ring forming fingers, which are yielding and springy in character, are given a set which will cause them to close and to hold in the closed ring forming relation when the ends 20 are entered in the slots in the tubular rib.

Actually, the fingers may be given a set which will cause the ends of the same, when not confined, to extend materially beyond the tubular rib so that when entered in the slots, they will 25 actually press against the far side of the tubular rib, as indicated at 10, so as to hold closed under spring tension and all to the same extent so that they will all be the same external size and shape.

If desired, the ends of the ring forming fingers and the slots in the rib may be slightly 30 offset, as disclosed in patent application, Serial No. 602,985, so as to require a slight lateral shifting or displacement of the ring ends to enter them in the slots in the closing operation to accomplish a binding holding engagement between the ring ends and slots.

For such constructions, special ring closing means may be employed, such as disclosed in co-pending patent application, Serial No. 150,432,

40 filed March 18, 1950, Patent No. 2,555,947, dated June 5, 1951, arranged to guide and shift the ring ends sufficiently to line them up and permit them to enter the slots.

However, in the present invention, with the 45 strong closing tension of the rings, it is not contemplated that any mechanical interlocking engagement between the ring ends and slots may be required.

With the ring forming fingers strongly biased in the ring closing direction, it is necessary to provide some means for overcoming the spring closing action and to open and hold the rings in opened relation while engaging the filler in the binding.

and 5 in the form of a die member 11 having a concave seat 12 of greater radius than the normal radius of the rings and a companion die member 13, designed to enter the rings and having a convex face 14 of substantially the same radius as the concave seat so that the two, in cooperative engagement with the rings, will have a tendency to bend the rings open, as shown in Figure 5.

These dies, as shown, are preferably of only such extent as to effect opening of the rings and are applied to the root end portions of the rings so as to leave the free end portions of the rings clear for the threading of the leaves or filler thereover.

These opening dies merely spring the rings open so that after the leaves are in place the rings will close of their own tension, as soon as the dies relax their grip.

If desired, the opening dies may have guiding surfaces for lining up and directing the ring ends into the slots as the rings spring back to closed relation or separate means may be provided for lining up and leading the ring ends into the rib slots.

The spring tensioned rings hold the leaves or filler securely in place in the binding, but they may be pried or forced open, if desired, for removal and replacement of sheets or fillers.

The absence of hooks, notches or locking shoulders on the ends of the rings is an advantage in the placing and removal of leaves and fillers. The ends of the ring forming fingers may be perfectly smooth and rounded so as to favor easy passage through perforations in the sheets to be bound and entry into the slots in the tubular rib.

The construction is simple to manufacture and in addition to mechanical advantages is neat and attractive in appearance and therefore suited to the binding of more or less expensive printed or other material.

The opening dies and, if used, the closing dies may, if required, be heated and/or cooled, as necessary, to impart proper curvature and spring set to the ring forming fingers to leave them, in the final form, with the necessary bias in the ring closing direction.

What is claimed is:

1. The mechanical binding herein disclosed and comprising a tubular rib having integral ring forming fingers projecting from one side, said tubular rib having slots in the opposite side to receive the ends of the ring forming fingers and

said ring forming fingers being flexible and springy in character and set to close to a diameter less than the ring diameter formed by entry of the ends of the fingers in the slots in the rib and whereby when the ends of said fingers are entered in said slots said fingers will be held engaged in said slots under the spring closing tension imparted by the set of the ring forming fingers.

2. A mechanical binding comprising a tubular rib having integral ring forming fingers projecting from one side, said rib having slots in the opposite side positioned and sized to receive the free ends of said ring forming fingers and said ring forming fingers being flexible and resilient and having a permanent set imparted thereto causing them to spring to a smaller diameter than that produced when the ends of the fingers are engaged in the slots and the end portions of said fingers being of a size to extend fully through said

15 slots into engagement with the further interior wall of the tubular rib and whereby the ends of the fingers held by the spring tension of the fingers in engagement with the far wall of the tubular rib will maintain the rings of the same

20 uniform size and shape.

25 3. The mechanical binding herein disclosed and comprising a tubular rib having integral ring forming fingers projecting from one side, said tubular rib having slots in the opposite side to

30 receive the ends of the ring forming fingers and said ring forming fingers being flexible and springy in character and set to close to a diameter less than the ring diameter formed by entry of the ends of the fingers in the slots in the rib and

35 whereby when the ends of said fingers are entered in said slots said fingers will be held engaged in said slots under the spring closing tension imparted by the set of the ring forming fingers, said fingers having substantially straight and smooth 40 side edges free of notches or hooks to thereby slide without obstruction into and out of said slots in the rib.
